UNITED STATES PATENT OFFICE

147,228

DESIGN FOR A MEDALLION OR SIMILAR ARTICLE

Amy J. Daniels, North Wilbraham, Mass.

Application April 23, 1946, Serial No. 128,878

Term of patent 14 years

(Cl. D29—19)

To all whom it may concern:

Be it known that I, Amy J. Daniels, a citizen of the United States, residing at North Wilbraham, in the county of Hampden and Commonwealth of Massachusetts, have invented a new, original, and ornamental Design for a Medallion or Similar Article, of which the following is a specification, reference being had to the accompanying drawings, forming part thereof:

Fig. 1 is a plan view of a medallion showing my new design; and

Fig. 2 is an edge view of the medallion shown in Fig. 1.

I claim:

The ornamental design for a medallion or similar article, as shown.

AMY J. DANIELS.
